Primary Examiner — Rashida Johnson(74) *Attorney, Agent, or Firm* — Howard Natter; Natter & Natter(57) **CLAIM**

The ornamental design for a double bell juncture for two woodwind instruments, as shown and described.

DESCRIPTION

FIG. 1 is a reduced perspective view of a double bell juncture for two woodwind instruments showing my new design; FIG. 2 is a top plan view;

FIG. 3 is a front elevational view;

FIG. 4 is a right side elevational view;

FIG. 5 is a left side elevational view;

FIG. 6 is a rear elevational view; and,

FIG. 7 is a bottom plan view.

The broken-line showing of FIG. 1 illustrates environmental structure that forms no part of the design to be patented.
